UNITED STATES PATENT OFFICE.

AXEL ANDERSON, OF AMERY, WISCONSIN, ASSIGNOR TO RUSSELL GRADEER MANUFACTURING CO., OF MINNEAPOLIS, MINNESOTA, A CORPORATION.

GRADING-MACHINE.

1,363,704.

Specification of Letters Patent. Patented Dec. 28, 1920.

Application filed May 27, 1918. Serial No. 236,768.

To all whom it may concern:

Be it known that I, AXEL ANDERSON, a citizen of the United States, resident of Amery, county of Polk, State of Wisconsin, have invented certain new and useful Improvements in Grading Machines, of which the following is a specification.

The object of my invention is to provide means for use in connection with a quick-lifting mechanism of a grader blade for obtaining a fine adjustment of the blade, either up or down, as the character of the work may seem advisable.

A further object is to provide a mechanism of simple construction and one which can be conveniently manipulated and will add comparatively little to the expense of construction.

The invention consists generally in various constructions and combinations, all as hereinafter described and particularly pointed out in the claims.

In the accompanying drawings forming part of this specification,

Figure 1 is a perspective view of a grading machine embodying my invention,

Fig. 2 is a detail side view of the blade adjusting mechanism,

Fig. 3 is a transverse sectional view through such mechanism.

In the drawing, 2 represents a frame having rear supporting wheels 3 and forward supporting and guiding wheels 4. 5 is a scraper blade carried by a ring 6 that is mounted on a tongue 7 that is pivoted at the forward end of the frame 2 for vertical oscillation. 8 is a shaft mounted transversely on the middle portion of the frame 2 and 9 are quadrants secured to the side rails of said frame upon opposite sides thereof and bridging the shaft 8. 10 represents levers loosely mounted on the shaft 8 and having locking latches 11 for engaging the teeth of the quadrants 9 to lock the levers 10 in any desired position. These levers are preferably provided with curved rack bars 12, preferably projecting rearwardly and downwardly from said levers, and secondary levers 13 are pivoted on the levers 10 at 14 and have locking latches 15 for engaging the teeth of the rack bars 12. Bell cranks 16 are mounted on the shaft 8 and have one arm pivotally connected by links 17 with lateral extensions 18 of the tongue 7 and the other

arms of the bell cranks extend above the 55 pivots 14 and are connected by links 19 with the secondary levers 13 near their pivots and preferably opposite the racks 9. The teeth of the rack bars 12 are much finer than those of the quadrants and when the scraper blade 60 has been adjusted in the desired position by the movement of the levers 10, which will provide for a quick raising or lowering of the scraper blade, the operator will lock these levers by means of their latches and 65 then by the oscillation of the secondary levers 13 over the small teeth, provided in the rack bars for that purpose, will be able to obtain a comparatively slow or fine adjustment of the scraper which would not be 70 possible through the operation of the main levers 10. It will be understood that when the latches of the main levers are released, movement will be imparted to the scraper blade through the rack bars and the secondary levers to the bell cranks, so that both 75 mechanisms will be operated simultaneously, that is, the secondary levers will move back and forth with the main levers for the quick adjustment of the scraper, but when this adjustment has been obtained and the operator may desire a still further slight adjustment, either up or down, he can accomplish it by the movement of the secondary levers independently of the main levers. It sometimes 80 happens in grading work that the operator of the machine wishes to raise or lower the scraper blade a little to accommodate it to some inequality of the roadway where the movement of the main levers a single notch 85 would be too great an adjustment, and by means of the secondary levers this fine or delicate adjustment may be easily obtained and the machine thereby be made capable of doing more accurate and better work than 90 95 would be possible with the single adjustment of the main levers.

I claim as my invention:

1. The combination, with a wheeled carrying frame and a scraper blade therefor, of a shaft mounted in said frame, levers loosely mounted on said shaft and having locking latches, and stationary quadrants having teeth for said latches, bell cranks loosely mounted on said shafts and having one arm 100 connected with said scraper blade and secondary levers mounted on said main levers for simultaneous movement therewith, and

means pivotally connecting said secondary levers with the other arm of said bell cranks.

2. The combination, with a frame having carrying wheels, of a scraper blade supported thereby, primary lifting levers pivoted on said frame, bell cranks concentrically mounted with respect to said lifting levers and connected with said scraper, and secondary levers pivoted on said primary levers and connected with said bell cranks, and means connecting said secondary levers with said primary levers for simultaneous movement therewith, or movement independently of said primary levers.
- 10 3. The combination, with a frame having

carrying wheels, of a scraper blade supported thereby, primary lifting levers pivoted on said frame, bell cranks pivoted on said frame, and connected with said scraper, secondary levers pivoted on said primary levers and connected with said bell cranks, and means connecting said secondary levers with said primary levers for simultaneous movement therewith or movement independently of said primary levers.

20 In witness whereof I have hereunto set my hand this 15th day of April, 1918.

25 AXEL ANDERSON.
